 WO 2015144990 10/2015

Primary Examiner — Selina Sikder(74) *Attorney, Agent, or Firm* — Merchant & Gould P.C.(57) **CLAIM**

The ornamental design for an optical structure, as shown and described.

DESCRIPTION

FIG. 1 is a top perspective view of an exemplary optical structure according to the present disclosure;

FIG. 2 is a bottom perspective view of the optical structure of FIG. 1;

FIG. 3 is a top view of the optical structure of FIG. 1;

FIG. 4 is a bottom view of the optical structure of FIG. 1;

FIG. 5 is a first side view of the optical structure of FIG. 1; and,

FIG. 6 is a second side view of the optical structure of FIG. 1 and rotated 90° from FIG. 5.

The broken lines represent portions of the structure that form no part of the claim.

1 Claim, 5 Drawing Sheets---
